UNITED STATES PATENT OFFICE

2,471,978

APPARATUS FOR OILING PARTS

Duer C. Robson, Baltimore, Md., assignor to Western Electric Company, Incorporated, New York, N. Y., a corporation of New York

Application December 21, 1945, Serial No. 636,403

4 Claims. (Cl. 184—102)

1

This invention relates to apparatus for oiling parts and more particularly relates to apparatus for oiling rollers of conveyer chains.

In the operation of conveyers having actuating rollers for actuating parts of the conveyers, it is necessary to oil the rollers. A conveyer having a large number of such rollers requires considerable time to oil the rollers manually.

An object of the invention is to provide new and improved apparatus for oiling parts.

Further objects of the invention are the provision of apparatus for automatically oiling rollers of conveyer chains while the conveyer chains are in use.

One apparatus embodying the invention includes a tank for retaining oil therein and a gravity-biased rocker pivotally attached to the tank and extending into the path of rollers of a conveyer chain. A wick secured to the rocker extends into the tank and wipes the rollers as they advance along the path, whereby the wick coats the rollers with oil.

A complete understanding of the invention may be obtained from the following detailed description of an apparatus for oiling parts forming one embodiment thereof, when read in conjunction with the appended drawing, in which

Fig. 1 is a fragmentary vertical section of an apparatus for oiling parts embodying the invention, and

Fig. 2 is a fragmentary section taken along line 2—2 of Fig. 1.

Referring now in detail to the drawing, a conveyer 10 (Fig. 1) includes tracks 11—11 along which tracks a roller chain 12 is advanced by suitable means (not shown). The roller chain is supported between the tracks by support rolls 15—15.

A trip roll 16 (Fig. 2) having a liner 18 positioned therein is secured by a bolt 19 upon an axle 20. The axle is secured to an extension 21 which is secured to supporting plate 22 carried by the chain 12.

A tank 25 for containing a supply of oil 26 has a bracket 27 projecting therefrom. A metallic arm 30 (Fig. 2) having a wick 32 fitted thereto is secured pivotally to the bracket 27 and is provided with a bracket 35 for this purpose.

A lower portion 36 of the metallic arm 30 is slightly curved and normally hangs in the path of the actuating roller 16. An upper portion 37 of the metallic arm is curved about a relatively short radius and the upper end 38 thereof normally engages the inner portion of the tank 25 and limits the downward movement of the lower portion 36 of the metallic arm. An end por-

2

tion 40 of the wick 32 is free and is positioned in the supply of oil 26, whereby the oil permeates the entire unimmersed portion of the wick by capillary action.

5 The trip roll 16 (Fig. 2) is provided with oil bores 41—41, which are aligned with the oil bores 42—42 formed in the liner 18. The oil passes through the bores 41—41 and 42—42 to the axle 20, whereby the relatively movable surface of the liner 18 and the axle 20 is coated with oil.

In the operation of the apparatus, the roller chain 12 (Fig. 1) is advanced along the tracks 11—11 by suitable advancing means (not shown) toward the right, as viewed in Fig. 1. The trip

15 roll 16 (Fig. 2) carried by the chain 12 is advanced into contact with the wick 32 and moves the wick and the metallic arm 30 upwardly as it is advanced therewith. Meanwhile, the trip roll 16 and the liner 18 are rotated on the axle 20 by the

20 drag of the wick 32 upon the trip roll. As the roll 16 rolls along the wick 32, the weight of the metallic arm 30 presses the wick tightly against the trip roll and oil which has permeated the wick is squeezed into the oil bores 41—41. The

25 oil passes through the oil bores 41—41 into the oil bores 42—42 formed in the liner 18 through which the oil passes to the axle 20, whereby the axle and the liner are lubricated. After the trip

30 roll 16 has been advanced out of contact with the wick 32, the lower portion of the metallic arm 30 drops to its full-line position so that the next trip rolls (not shown) carried by the roller chain 12 will contact the wick 32, and the operation described hereinabove will be repeated.

35 The apparatus described hereinabove serves to lubricate trip rolls, illustrated by the trip roll 16 efficiently and automatically. The only attention required for the apparatus is that the supply of oil 26 must be replenished when necessary to prevent complete depletion thereof. Thus

40 large numbers of actuated rolls may be lubricated automatically.

What is claimed is:

1. In a conveyer including a track and a conveyer element which may be advanced along the track in a predetermined direction, an oiler which comprises an oil tank positioned above the track, an arm pivotally connected to the oil tank with the lower end thereof urged by gravity into the path of the conveyer element, and a wick covering the approach side of the arm and extending into the tank, whereby oil in the tank is conducted by the wick to the conveyer element.

2. In a conveyer including a conveyer element and a track for guiding a conveyer element there-

along as the conveyer element is advanced in a predetermined direction, an oiler which comprises a tank for retaining a supply of oil therein, a curved arm pivotally attached to the tank in such a position that the upper end thereof projects into the tank and the lower end thereof is forced by gravity into the path of the conveyer element, the approach side of the arm being convex, and a wick extending along the approach side of the arm from the lower end of the arm to the upper portion thereof and depending into the supply of oil, whereby the conveyer element contacts the wick as it is advanced past the oiler and the arm squeezes oil out of the wick onto the conveyer element.

3. In a conveyer including a conveyer element having a trip roll projecting laterally therefrom and a track for guiding the conveyer element therealong in a predetermined direction, an oiler which comprises a tank positioned above the track for retaining a supply of oil, a curved arm pivotally mounted on the tank with the lower end thereof extending downwardly into the path of the trip roll, and a wick serving as a facing for the approach side of the arm, the upper end of the wick extending beyond the upper end of the arm and projecting into the supply of oil, whereby oil is conveyed by capillary action from the upper end of the wick to the lower end thereof and is squeezed therefrom upon the trip roll when the roll is advanced into contact with the wick.

4. In a conveyer including a pair of tracks, a roller chain guided along the pair of tracks in a

predetermined direction, a laterally projecting axle carried by the roller chain, a hollow roll having a bore extending from the exterior thereof to the interior thereof mounted rotatably upon the axle, an oiler which comprises a tank positioned above the tracks for containing oil, an arm pivotally secured to the tank, the upper end of said arm being curved, having a short radius and projecting into the tank and the lower end of the arm depending into the path of the hollow roll, and a facing of wick material extending from the lower end of the approach side of the arm into the supply of oil, the roll serving to engage and roll along the facing when it is advanced past the oiler, whereby the lower end of the facing and the lower end of the arm are forced upwardly and oil is squeezed from the facing into the bores formed in the roll.
